UNITED STATES PATENT OFFICE.

JAMES TIMMS, OF COLUMBUS, OHIO, ASSIGNOR TO THE BUCKEYE MALLEABLE IRON AND COUPLER COMPANY, OF COLUMBUS, OHIO.

FRICITION DRAFT-GEARING AND BUFFING APPARATUS.

SPECIFICATION forming part of Letters Patent No. 740,335, dated September 29, 1903.

Application filed October 13, 1902. Serial No. 127,064. (No model.)

To all whom it may concern:

Be it known that I, JAMES TIMMS, of Columbus, in the county of Franklin and State of Ohio, have invented certain new and useful

5 Improvements in Friction Draft-Gearing and Buffing Apparatus; and I do hereby declare the following to be a full, clear, and exact description of the invention, such as will enable others skilled in the art to which it appertains 10 to make and use the same.

My invention relates to an improvement in friction draft-gearing and buffing apparatus, the object of the invention being to provide improvements of this character in which the 15 friction of the parts will be very great and in which the friction increases from the least to the greatest buffing movement of the gear.

With this object in view the invention consists in certain novel features of construction 20 and combinations and arrangements of parts, as will be more fully hereinafter described, and pointed out in the claims.

In the accompanying drawings, Figure 1 is an elevation illustrating my improvements. 25 Fig. 2 is a longitudinal sectional view, and Fig. 3 is a cross-section.

1 represents parallel draft-irons secured to the draft-timbers of the car and cast with pockets or seats 2 for end followers 3, around 30 which a yoke-strap 4 is passed and secured to the draw-bar 5 of the coupling. These followers 3 are provided at their opposite ends with projecting beveled blocks or bearing-faces 6, which bear against the beveled or 35 wedge-shaped ends 7^a of friction-plates 7, which extend from one follower to the other, and it is the wedge shape of these ends 7^a which gives to the gear the increased friction, as will more fully hereinafter appear.

40 Against the inner faces of wedge-shaped ends 7^a inside followers 8 are located and made with beveled faces 9 to bear against the wedges. These inside follower-plates 8 are recessed, forming seats for coiled springs 11 and 45 12, compressed between them, there being, preferably, five of the smaller springs 11, located one at each corner of the plates and one at the center, and one of the larger springs 12 surrounding the central spring 11. The 50 springs serve to hold the inside follower-plates 8 against the inner faces of wedge-shaped ends

7^a of friction-plates 7, pressing the latter apart and holding said wedge-shaped ends against the beveled ends of followers 3, pressing the latter apart and against the ends of 55 their seats in draft-irons 1.

The operation of my improvements is as follows: When there is pressure or a pull upon the draft-gear, one end follower 3 is moved toward the other, the latter being stopped by 60 its seat in draft-iron 1. The beveled or inclined ends 6 of followers 3, engaging the wedge-shaped ends 7^a of friction-plates 7, force the friction-plates toward each other, and as the wedges 7^a engage the beveled or 65 inclined outer faces of inside follower-plates 10 the latter are forced toward each other, contracting the springs, thus taking up the jar, and the springs will return the parts to their 70 normal positions when strain is discontinued.

By constructing the ends 7^a of friction-plates 7 in the form of wedges, as shown, it will be seen that the friction of the followers 3, ends 7^a, and inside follower-plates 10 is very great and that the frictional engagement increases 75 the more the inside follower-plates 10 move toward each other, as the width of the wedges increases from their outer to their inner ends, thus increasing the friction, to take up great jars and at the same time permitting slight 80 jars to be compensated for as well.

A great many changes might be made in the general form and arrangement of the parts described without departing from my invention, and hence I do not confine myself to the 85 precise construction set forth, but consider myself at liberty to make such slight changes and alterations as fairly fall within the spirit and scope of my invention.

Having fully described my invention, what 90 I claim as new, and desire to secure by Letters Patent, is—

1. In a friction draft-gear the combination with two end followers constructed with converging inclined faces and two interposed 95 friction members each having outwardly-flaring wedge-shaped ends which contact with the end followers, and are forced inwardly thereby, and two inner followers each provided with converging inclined faces, which engage 100 the inner inclined faces of the wedge-shaped ends of said friction elements and force the

latter outwardly, and a spring interposed between the inner followers, substantially as set forth.

2. In a friction draft-gear the combination with two end followers each constructed with converging inclined faces and two interposed friction members or elements each having outwardly-inclined wedge-shaped ends which contact with the end followers and are forced inwardly thereby, the flaring ends of each member being rigidly connected by side pieces, of two inner followers and an interposed spring which serve to force the interposed friction elements outwardly, substantially as set forth.

3. In a friction draft-gear, the combination with two end followers each constructed with converging inclined faces and two interposed friction elements each provided with outwardly-inclined wedge-shaped ends which contact with the end followers and are forced inwardly thereby, of two inner followers each of which is provided with converging inclined faces that engage the inclined wedge-shaped ends of said friction elements and force the latter outwardly, and a series of springs interposed between the inner followers, substantially as set forth.

4. In a friction draft-gear and buffing apparatus, the combination with two end fol-

lowers having projecting beveled blocks or bearing - faces, of friction - plates having wedges at both ends against the bearing-blocks of the respective end followers and of greatest thickness adjacent to the plate and diminishing in thickness to their free ends, a second set of followers having beveled ends contacting with the inner faces of said wedge-shaped ends of the friction-plates and a spring forcing said last-mentioned followers apart.

5. In a draw-gear and buffing apparatus the combination with end follower-plates each having opposite inwardly-inclined faces forming wedges, of opposite inside wedges having outwardly-inclined faces, each face forming an angle with the opposite faces on the end follower-plates, of two pairs of connected wedges each having outside faces that contact with the bevels on the end follower-plates and inside faces that contact with the bevels on the inside wedges, and a spring pressing the inside wedges in opposite directions.

In testimony whereof I have signed this specification in the presence of two subscribing witnesses.

JAMES TIMMS.
